PROCESS FOR TREATING HYDROCARBONS

Carbon P. Dubbs, Chicago, Ill., assignor to Universal Oil Products Company, Chicago, Ill., a corporation of South Dakota

Continuation of application Serial No. 136,426, September 20, 1926. This application January 22, 1932, Serial No. 588,107

1 Claim. (Cl. 196—58)

This application is a continuation of my application, Serial No. 136,426, filed September 20, 1926.

In the conversion of high boiling point petroleums into lower boiling point petroleums by subjecting such petroleum to the action of heat under pressure, it is believed that the total coke produced is from two causes, namely—that part of the coke is produced from the splitting or 10 breaking up of portions of higher boiling point oils into the desired lower boiling point oils and that the rest of the coke is produced by maintaining the heavy liquid residue from the above reaction, separated from the lower boiling point 15 products produced, at a temperature which causes a substantial portion of this heavy liquid residue to be converted to coke-like bodies, and it seems that this temperature can be substantially below that point at which any substantial portion of the heavy oil will be converted into 20 the desirable lower boiling point oils, such as commercial gasoline.

Whether the above is true or not, I have found that as soon as the first reaction is over (conversion of the higher boiling point hydrocarbons into desirable lower boiling point oils) that by immediately reducing the temperature of the heavy liquid residue, the formation of coke is substantially arrested and the total amount produced is materially below that produced when the temperature of said liquid residue is not immediately substantially reduced.

It is a well known fact that the heavy oils, or the heavier portions of the lighter oils, produce 35 a great deal more coke for a given amount of cracking than do the light oils or lighter ends of the oil. For instance, there is a great deal more coke produced by cracking a 10 Baumé gravity California oil to produce 25% gasoline than there is from producing the same amount of gasoline from cracking a 24 Baumé gravity California oil; therefore, it is of great economic 40 value to have a process and apparatus that will utilize the heat contained in a cracked light oil to automatically separate the light from the heavy ends of another oil, and permit of the withdrawal of the heavy ends of this oil along 45 with the heavy ends of the cracked oil, thus avoiding over-cracking or superheating of the heavy ends of the oil, thereby avoiding a heavy production of coke.

There are various methods of accomplishing the above objects and my invention covers broadly all of the various methods. In the following 50 description, there is set forth an economical and

practical method and apparatus suitable for accomplishing these objects and it will be understood that the particular apparatus I have shown is susceptible of wide changes and still be within the principle taught in this invention.

In the drawings, Fig. 1 and Fig. 1A are a side elevational schematic or diagrammatic view, partly in vertical section of an apparatus in which the process may be carried out.

Those versed in the art will fully understand 10 the methods of calculating to determine the sizes of the different parts of apparatus suitable for the particular operation they may desire to follow in the use of this process.

I wish to particularly point out that this process is susceptible to wide variations as to temperatures and pressures used, which are of great value to the industry, as they permit the operation of the plant to be varied to suit the particular needs of the refiner for his particular 20 market and conditions, and also for the various oils used in this art.

The following description will illustrate a method by which the purposes of the present invention can be accomplished. The oil to be treated 25 is drawn from any suitable source (not shown) through lines 1 and 3, having pump 2 interposed therein. From line 3, the oil may be forced through line 6 by opening valves 5 and 7 (valve 8 being closed) through the heat interchanger 30 9, which may be of any suitable design. The preheated oil may then pass through valve 10, back into line 6, through valve 11, being discharged into the dephlegmator 12. This dephlegmator may be of any design suitable for 35 producing the desired results.

As it passes through the heat interchanger 9, the charging stock is preheated by the hot vapors being cooled therein. After being discharged into the dephlegmator 12, through line 6, it is 40 further heated by intimately commingling with the hot vapors and condensate therein. This vaporizes the gasoline content of the charging stock, said vapors passing out of the dephlegmator 12 with the low boiling point vapors produced by cracking the oil as will be later described.

These vapors pass out through vapor outlet 13, controlled by valve 13', through heat interchanger 9, thence through line 14, controlled by 50 valve 14', into condensing coils 15, contained in condensing box 16, where condensation takes place, the condensed liquid passing through line 17, controlled by valve 17', into distillate receiving tank 18 provided with liquid draw-off line 19, 55

controlled by valve 20; 21 is a pressure gauge and 22 is a liquid level gauge. The uncondensable gas is led off through line 23, controlled by valve 24.

- 5 The unvaporized portion of the raw oil, continuously injected into dephlegmator 12, mixes with the reflux condensate produced in said dephlegmator 12, said mixture collecting on the dividing partition plate 25 being withdrawn 10 through line 26, controlled by valve 27 (valve 30 being closed) and discharging into the lower part of dephlegmator 12. The plate 25 divides the dephlegmator into upper and lower compartments or sections. From the lower section of the 15 dephlegmator, the oil is withdrawn through line 28, controlled by valve 29, into line 31, controlled by valve 32 (valve 33 in line 32a being closed) into pump 34 (valve 35 being closed in line 36). The pump forces the oil through line 20 38, controlled by valve 39, into line 38a (valve 31 in line 51 being closed), valve 39a being open, the oil discharging into line 40, from which it passes through heating tubes 41, positioned in a suitable furnace 42.
- 25 The oil as it passes through tubes 41 is brought to a conversion temperature of, say 750° to 1200° F., more or less. The heated oil is then transferred through line 43, controlled by valve 46, and discharges into reaction chamber 47 where 30 reaction occurs. The products of reaction are discharged together from the lower end of reaction chamber 47, through line 48, controlled by valve 49. From pump 34 to control valve 49, in this particular run, the pressure will be, say 35 from 50 to 1200 pounds, more or less, according to the oil being treated and the results desired. Beyond the control valve 49, the balance of the apparatus may be at a reduced pressure, down to or sufficiently above atmospheric to control the 40 flow of material in the different parts of the apparatus.

The products of reaction from chamber 47 may pass through line 50 into line 51, valves 52, 45 53 and 54 being closed. Valves 53 and 54 on lines 55 and 56 are for use should valve 49 clog up, in which case, either line 56 and valve 53, or line 55 and valve 54 can then be used. Valve 57 is left open, and the products of reaction discharged into what may be termed a separator 50 chamber 58. Any hydrocarbons in liquid form discharging into separator chamber 58 are immediately reduced in temperature, due to the fact that a portion of their heat is constantly used to convert these liquid hydrocarbons into 55 vapor, the amount so converted into vapor being dependent of course, upon the amount of latent heat contained in this oil when the pressure is reduced. In this manner, I substantially prevent the excessive formation of carbon from the second reaction in chamber 58.

If all of the volatile portion of the oil being treated is converted into vapors, then the greatest amount of coke will accumulate in separator 58, while a small amount of coke will accumulate 60 in reaction chamber 47. Therefore, these should preferably be built in proper proportion, according to the operation desired on any particular plant.

When it becomes desirable to remove the coke 70 and clean the separator chamber 58 and reaction chamber 47, the manheads 59, 60, 61 and 62 are removed after the plant has been properly cooled and the coke is preferably removed through lower manholes 59 and 62.

75 If there is a liquid accumulation in separator

58, then the same is withdrawn through line 64, controlled by valve 63, and passed to suitable storage (not shown). Should this valve 63 clog, then valve 65 and line 66, or valve 67 on line 68 may be used. The vapors from the separator 58 pass out through line 69, controlled by valve 70, into the lower section of the dephlegmator 12, and as the vapors pass upwardly through the dephlegmator, they are cooled by the oil flowing downward through said dephlegmator. This 10 condenses the heavier ends of the vapors, and this condensate with the unvaporized portion of charging stock may be drawn off through line 28, through valves 29 and 32, through pump 34, and returned through line 38a, valve 39a, line 15 40 to the heating tubes 41.

The remaining vapors pass out through line 13, heat interchanger 9, line 14, condenser 15, line 17, the condensed liquid collecting in receiving tank 18, as previously described. Should the 20 vapors coming out of dephlegmator 12 through line 13, contain an undesirable portion of vapors having boiling points higher than those desired, these are condensed by taking some of the distillate collected in receiver 18 and passing it 25 through line 71, controlled by valve 71', through pump 72 and line 74 (valve 73 being open), into the upper portion of dephlegmator 12 in such quantities as will bring about the desired result.

On the other hand, should the operation be 30 such that the quantity of the charging stock pre-heated in the heat interchanger 9 results in excessive cooling, then portions or all of said charging stock may be diverted directly to the heating tubes 41 by the manipulation of valves 11 and 77 35 and such portion of charging stock not desired in the dephlegmator 12 can be passed through lines 77a and 78, controlled by valve 80, to heating tubes 41; or, if it is desired that the charging stock be not preheated, or a portion of it not be pre-heated, then it may be discharged directly into the heating tubes 41 by obvious manipulation of valve 75, passing this portion of charging stock through line 76 into line 78 and into the heating tubes 41, valve 77 in this case being closed. Valve 45 79 in line 78 is normally kept closed, it being used only in cases of emergency to empty the plant of its oil content.

If in a particular operation it is desirable to bring the oil to a temperature within the above 50 described ranges, that is, 750° F. to 1200° F. in the heating tubes 41 and maintain the oil under a range of pressure already described, i. e. 50 to 1500 pounds to the square inch up to valve 49, and this results in an excessive quantity of oil 55 being vaporized in separator 58, and it is desirable to have a greater portion of the hydrocarbons being treated, collect in the form of liquid in separator 58, this can be brought about by directing the necessary quantity of cold charging 60 stock from pump 2, through valve 75, line 76 (valve 77 being closed) into line 78 (valves 79 and 80 being closed), through line 81, (valve 52 being opened). Thus the charging stock is injected into the hot products of reaction passing through 65 line 51 and brings about the desired cooling. This results in the heavy ends of the products of reaction being collected as a liquid in separator chamber 58, and in addition, all but the heavy ends of the charging stock are evaporated 70 leaving these latter heavy ends as a liquid. The liquid may be withdrawn through line 64. It will be found that this withdrawn residue is comparatively free of any solid matter, and is a suitable fuel for marketing purposes.

There is another important feature of the present invention, as follows: By this mode of operation, it will be readily seen that in the separator chamber 58, the lighter ends of the charging stock are vaporized and thus separated from the heavy ends. Only the former eventually go to the cracking tubes 41, while the heavy ends are withdrawn from the bottom of separator 58 as residuum, which is of great economical value, as it is these heavy ends that produce a great volume of the coke when subjected to cracking.

One versed in the art will readily understand that no absolute temperatures or pressures can be laid down suitable for all oils and conditions, but that a few preliminary runs will give the best operating temperatures and pressures for the particular oil to be used and products desired.

I desire to call particular attention to a condition of operation in which it is desirable to heat the oil as it passes through the tubes to a relatively low temperature, that is, for that particular oil the temperature used will result in a low conversion into the desired low boiling point products. If the apparatus throughout is maintained under a uniform pressure, there will not be sufficient oil vaporized or vapors entering dephlegmator 12 to furnish sufficient volume of condensate in the dephlegmator for return to the heating tubes mixed with a fresh supply of raw oil. This portion of reflux can be increased by proportionately decreasing the pressure on the separator 58, a higher pressure being maintained on the reaction chamber 47 and heating tubes 41 by manipulating valve 49. Under these conditions, the decrease in the pressure on separator chamber 58 proportionately increases the amount of treated oil that can be withdrawn from this separator chamber in the shape of vapors.

There will be occasions when the particular oil being used and the degree of cracking such that it will be desirable to by-pass the separator 58, in which case, valve 57 is closed and valve 82 in line 83 opened. Valve 70 in line 69 is closed, thus making the discharge from reaction chamber 47 directly into the lower section of dephlegmator 12, in which case, valve 27 may be closed and valve 30 opened. The condensate collecting in the lower section below pan 25 falls to the bottom of dephlegmator 12 and joins any unvaporized hydrocarbons entering the lower section of dephlegmator 12, being withdrawn and passed through line 28, valve 35 and line 36 to suitable storage. This withdrawn liquid will be found to be a very high grade fuel with very little, if any, solid matter. The remaining vapors pass up through pipes 85 into the upper section of dephlegmator 12 and as they pass through the upper section of dephlegmator 12, the heavier ends are condensed, collecting on pan 25 along with any unvaporized oil injected into the dephlegmator above pan 25. This liquid oil is drawn off through line 26, valve 30, line 31, valve 32, and by pump 34 is forced through line 38, valve 39 (valve 33 being closed) line 38a, valve 39a, line 40 into heating tubes 41. The remaining vapors pass from the top of dephlegmator 12 through line 13, as already described.

The particular dephlegmator that I have shown, may contain two reboiling pans marked 84. These are for the purpose of catching the condensate and forming a pool in the path where the vapors are the hottest, these vapors tending to boil the light ends that may be contained in

the condensate. 84a are the overflow lines. Perforated pans 86 are also shown. It will be understood that one or a series of dephlegmators may be used of any desired design and size. 92 and 93 are liquid level gauge glasses. 94 are liquid try-cocks.

The parts of the apparatus to be insulated to prevent loss of heat by radiation are indicated by broken lines.

To a certain degree, the percentage of a particular oil passing through the tubes that can be cracked into the desired low boiling point products without depositing a substantial amount of carbon in the tubes, is dependent upon the pressure maintained on the oil, that is, the percentage of cracking can be increased to a certain extent by increasing the pressure. Hence, those versed in the art will be governed as to what pressure they shall select for their particular operation.

I have also discovered the fact that in cracking oil commercially, it is of very great importance to mix the heavier ends of the condensed vapors of a previous cracking operation with the raw oil and subject this mixture to cracking heat. It will be understood that while increased pressures permit more cracking of the oil in each passage through the tubes, that the same result can be accomplished by mixing more of the heavy condensed ends of previously cracked oil with the raw oil. As this mixture passes through the tubes, it should be maintained at a lower pressure and not subjected to as high a degree of cracking as when using a higher pressure. By repeatedly recirculating the heavy ends of the vapors of a previous cracking back through the heating tubes, one is enabled to obtain any desired ultimate yield up to complete conversion. This applies regardless of pressure used. The lower pressures, of course, will necessitate greater refluxing, but will give the advantage of higher velocity of the oil through the tubes which is beneficial. Each operation has its advantages and disadvantages and the conditions selected, will be governed by the particular oil being treated and products desired.

Another point I wish to particularly cover in this application is, that by varying the degree of pressure on the separator 58 by valve 70, the rates of vapor to liquid withdrawn from separator 58 can be varied. There will be certain operations where this mode of operation is very advantageous, such operations being where the operator desires to increase the amount of liquids withdrawn from separator chamber 58 over that obtained by lower pressures. There may be occasions when it will be found advantageous to maintain separator chamber 58 at the same pressure as reaction chamber 47. Likewise, there will be times when it will be found advantageous to operate the entire apparatus under a uniform pressure, in which case, the pressure may be controlled by the release of the uncondensable gas from receiving tank 18.

Having thus described my invention, what I claim is:—

A cracking process which comprises passing hydrocarbon oil in a restricted stream through a heating zone and heating the same therein to cracking temperature under pressure, discharging the heated oil into the upper portion of a vertically elongated reaction zone maintained under cracking conditions of temperature and pressure, passing both vapors and liquid oil downwardly through the reaction zone and re-

moving the same as a mixture from the lower portion of the reaction zone, simultaneously advancing a continuous stream of charging oil toward the process under a mechanically applied pressure, dividing the stream of charging oil into separate portions and commingling one of these portions with the mixture of vapors and liquid oil withdrawn from the lower portion of the reaction zone, separating the thus commingled hy-

drocarbons into vapors and residue in a separating zone maintained under lower pressure than the reaction zone, fractionating the separated vapors in contact with another of said portions of the charging oil stream, supplying the resultant mixture of reflux condensate and charging oil to the heating zone, and finally condensing the fractionated vapors.
